UNITED STATES PATENT OFFICE.

LEAL L. MONTGOMERY, OF SUPERIOR, WISCONSIN.

VIBRATOR.

1,117,884.

Specification of Letters Patent. Patented Nov. 17, 1914.

Application filed January 30, 1914. Serial No. 815,415.

To all whom it may concern:

Be it known that I, LEAL L. MONTGOMERY, a citizen of the United States, and a resident of Superior, in the county of Douglas 5 and State of Wisconsin, have invented a new and Improved Vibrator, of which the following is a full, clear, and exact description.

My invention relates to vibrators used for 10 massage purposes, and has reference more particularly to vibrators actuated by elastic fluid.

The object of the device is to provide a 15 simple, compact, strong and inexpensive device which is automatic in its action, which has few parts to get out of order and therefore reduces the cost of the device and its up-keep to a minimum.

I attain the above object by providing 20 a plunger adapted to be actuated periodically by elastic fluid operable means, with means for returning the plunger to its normal position.

The invention consists of the construction 25 and combination of parts to be more fully described hereinafter and fully set forth in the claims.

Reference is to be had to the accompanying 30 drawings forming a part of this specification, in which like characters indicate corresponding parts in all the views and in which:

Figure 1 is an axial, vertical section 35 through an embodiment of my invention; Fig. 2 is a similar view showing the plunger under the action of the piston; Fig. 3 is a perspective view of the device; and Fig. 4 is a section on line 4—4, Fig. 1.

Referring to the drawings, 5 represents 40 the shell or cylinder closed at the ends by means of plugs 6 and 7, preferably threaded therein. Air inlets 8 are provided in the cylinder adjacent the plugs 6 and 7; and similar air outlets 9 are provided in the 45 cylinder, which are closer to the plugs 6 and 7 than the inlets 8. Said outlets 9 are interconnected by a tubular member 10 forming an extension of the cylinder and which extension is provided with a lateral 50 aperture 11 formed in the central lateral extension 12 of the shell or cylinder 5. Threaded with one end into said aperture 11 is a tubular member 13 which forms a stem or support for a handle 14 to which 55 the cylinder 5 is secured by means of a nipple 15, to which nipple the intake 16 of a

vacuum pump can be secured. Between the projection 12 and the handle 14 a rubber washer 17 is interposed, whereby the vibration on the handle due to the reciprocating motion of the parts in the cylinder is reduced.

Mounted within the cylinder 5 is a valve 60 formed of two cup-shaped members 18 facing each other and interconnected by means of a stem or rod 19. The length of each of said cup-shaped members 18 is such that when the member covers the inlet 8 it uncovers the corresponding outlet 9, and vice versa. The length of said rod 19 is such 65 that when one of the members 18 uncovers the air outlet 9, the other of said members uncovers the inlet 8, i. e., when the valve uncovers the air outlet at one end, it simultaneously uncovers the air inlet at the opposite end. Mounted to slide on the rod 19 is a sleeve 21 forming the piston in the cylinder, the ends 22 of which are reduced 70 to fit snugly into the cups 18. Each of said cups at the bottom thereof carry a resilient member 23 which is adapted to be engaged by the corresponding extremity of the reduced end 22 of the piston, thereby closing the apertures 24 provided in the bottom of the cups, which apertures establish 75 communication between the spaces *a* and *b* at each side of said bottom.

The plug 7 is provided with an axial aperture 25 enlarged at the inner end of the plug, as shown at 26. Engaging the 80 aperture 25 is a plunger 27 the head 28 of which fits into the enlarged portion 26. A coil spring 29 carried by the plunger is also positioned in said enlarged portion and adapted to maintain the said plunger in 85 normal position. The projecting end of the plunger 27 is threaded and thereon adapted to receive members suitable for massage, of which 30 is one. The head 28 of said plunger is provided with a recess into which 90 is fitted a bumper 31, preferably of rubber, against which the valve strikes when the piston moves toward the plunger, as shown in Fig. 2. The plug 6 at its inner end is also provided with a bumper 32 against 95 which the opposite end of the valve is adapted to strike when the same is moved away from its engagement with the plunger by the movement of the cylinder in the direction opposite to that stated before, the 100 position of which is shown in Fig. 1. Both 105 of said bumpers are intended for the purpose

pose of reducing the vibration caused by the reciprocating movement of the plunger and valve in the cylinder.

The action of my device is as follows: The air drawn by the suction pump from the spaces *a* and *b*, see Fig. 1, through the outlet 9, reduces the pressure therein and permits the atmospheric pressure acting through the inlet 8 to force the piston 21 to move from its position shown in Fig. 1 toward the cup 18 at the right side of the plunger in said figure. The momentum of said piston, when it strikes the bottom of the cup 18 moves the valve therewith and causes the same to strike the bumper 31, thus forcing the plunger out of the plug 7. This movement of the valve uncovers the air outlet 9 at the opposite end of the cylinder, closing the inlet 8 at the same end, thus reducing the pressure in the spaces *a* and *b* formed by the sleeve, cup and cylinder at the said end of the cylinder and causing the return of the piston 21 and the valve therewith to the position shown in Fig. 1; thus a complete cycle of the piston and valve have been described. The purpose of the coil spring 29 in the plug 7 is not only to restore the plunger 27 to its normal position but also to reduce the shock caused by the valve striking the bumper 31 of the plunger.

The sleeve or piston 21 and the cup-shaped members 18 are made to fit snugly into the cylinder so as to reduce the leakage of air therebetween to a minimum. Furthermore, the sliding movement of said piston or sleeve 21 and the stem 19 of the valve is of such a nature as to produce a momentum which will not only be able to carry the valve to a desired position but to cause the plunger 27 to move a predetermined distance through the cylinder. Said bumpers 31 and 32 not only reduce the shock caused by the reciprocating movement of the piston and valve but reduce the noise that may be caused by the engagement of the metallic parts of the cylinder.

It is evident that various changes might be made and modifications resorted to in the construction and arrangement of the parts described without departing from the spirit and scope of my invention; hence, I do not wish to limit myself to the exact construction shown.

Having thus described my invention, I claim as new and desire to secure by Letters Patent:

1. In a vibrator, a plunger; elastic fluid operable means for actuating the plunger periodically; a member carried by the plunger and adapted to be engaged by said fluid operable means whereby the noise and shock of engagement is diminished; and means for returning said plunger to its normal position.

2. In a vibrator, a plunger; elastic fluid

operable means for actuating the plunger periodically; an elastic member carried by the plunger and adapted to be engaged by said fluid operable means; and resilient means associated with said plunger for restoring the same to its normal position.

3. In a vibrator, a cylinder; a plunger projecting from one end of said cylinder; means positioned in said cylinder and operable by a pressure reduction in said cylinder whereby said means will force said plunger periodically out of said cylinder; means for restoring said plunger to its normal position; and bumpers carried by said plunger and cylinder and adapted to reduce the vibration caused by the movement of said means.

4. In a vibrator, a cylinder; a plunger projecting through one end of said cylinder; a piston in said cylinder; means for reciprocating said piston by reducing the pressure in said cylinder, whereby the plunger is periodically moved by the piston out of the cylinder; means restoring said plunger to its normal position; and means carried by said plunger and cylinder and adapted to be engaged by said piston whereby the vibration, due to the engagement of said piston with the cylinder and the plunger, is reduced.

5. In a vibrator, a cylinder; a plunger projecting through one end of said cylinder, said cylinder having an air inlet and an air outlet adjacent the ends thereof; a valve for said inlets and outlets; a piston carried by said valve; means for exhausting air from the cylinder through the outlets whereby the piston is reciprocated with said valve whereby said valve is adapted to force said plunger periodically out of the cylinder; and means for restoring the plunger to its normal position.

6. In a vibrator, a cylinder; a plunger projecting through one end of said cylinder, said cylinder having an air inlet and an air outlet adjacent the ends thereof; a valve for said inlets and outlets; a piston carried by said valve; means for exhausting air from the cylinder through the outlets whereby the piston is reciprocated with said valve and said valve is adapted to force said plunger periodically out of the cylinder; means for restoring the plunger to its normal position; and bumpers carried by said cylinder and plunger and adapted to be engaged by said valve thereby reducing the vibration caused by the engagement of said valve with the plunger and cylinder.

7. In a vibrator, a cylinder; a plunger projecting through one end of said cylinder, said cylinder having air inlets and air outlets adjacent the ends thereof; a valve adapted to open or close simultaneously the inlets and outlets at opposite ends; a piston carried by said valve; means for reducing

the air pressure in said cylinder through the air outlet of the same whereby said piston is reciprocated on said valve and therewith in said cylinder causing a periodical engagement of the valve with the plunger, thereby forcing the plunger out of the cylinder; and means for restoring the plunger to its normal position.

8. In a vibrator, a cylinder; a plunger projecting through one end of said cylinder, said cylinder having air inlets and air outlets adjacent the ends thereof; a valve adapted to open or close simultaneously the inlets and outlets at opposite ends; a piston carried by said valve; means for reducing air pressure in said cylinder through the air outlet of the same whereby said piston is reciprocated on said valve and therewith in said cylinder causing a periodical engagement of the valve with the plunger, thereby forcing the plunger out of the cylinder; means for restoring the plunger to its normal position; and rubber bumpers carried by said plunger and cylinder and adapted to be engaged by said valve substantially as and for the purpose set forth.

9. In a vibrator, a cylinder; a plunger projecting through one end of said cylinder, said cylinder having air inlets and air outlets adjacent the ends thereof, said inlets being nearer the ends; a valve adapted to open or close simultaneously the inlets and outlets at opposite ends; a piston carried by said valve; means for reducing air pressure in said cylinder through the air outlets of the same whereby said piston is reciprocated on said valve and therewith in said cylinder causing a periodical engagement of the valve with the plunger, thereby forcing the plunger out of the cylinder; means for restoring the plunger to its normal position; and rubber bumpers carried by said plunger and cylinder and adapted to be engaged by said valve alternately, substantially as and for the purpose set forth.

10. In a vibrator, a shell; plugs at the extremities of said shell; a plunger carried by one of said plugs projecting out of and into said shell, said shell having apertures adjacent the plugs forming air inlets

and air outlets, said outlets being nearer to the plugs than the inlets; a cup-shaped member for controlling the inlet and outlet at each end of said shell; a stem connecting said cup-shaped members; a sleeve fitting snugly on said stem and into said shell adapted to reciprocate between said cup-shaped members, said cup-shaped members having means adapted to establish communication between the spaces in the cylinder formed by the plug with the cup-shaped member and the sleeve with the same; and means for reducing the pressure in said spaces through the air outlets in the shell whereby said sleeve is reciprocated on said stem and in said shell with said cup-shaped members.

11. In a vibrator, a shell; plugs at the extremities of said shell; a plunger carried by one of said plugs projecting out of and into said shell, said shell having apertures adjacent the plug forming air inlets and air outlets, said outlets being nearer the plugs than the inlets; a cup-shaped member fitting snugly into the shell for controlling the inlets and outlets at each end of said shell; a stem connecting said cup-shaped members; a sleeve fitting snugly into said shell and on to said stem and adapted to reciprocate on said stem and therewith in said shell, said cup-shaped members having means adapted to establish communication between the spaces in the shell formed by the plug with the cup and the cup with the sleeve; means for reducing the pressure in said spaces through the air outlets in the shell whereby said sleeve is reciprocated on said stem and in said shell with said cup-shaped member and stem whereby the plunger is periodically forced out of the shell; and resilient means associated with the plunger for restoring the same to its normal position.

In testimony whereof I have signed my name to this specification in the presence of two subscribing witnesses.
